WASHING APPARATUS

Filed June 21, 1930

INVENTOR.
George Geddes
BY John Donaldson
ATTORNEY.

UNITED STATES PATENT OFFICE

GEORGE GEDDES, OF DETROIT, MICHIGAN

WASHING APPARATUS

Application filed June 21, 1930. Serial No. 462,796.

My invention relates to a new and useful improvement in a washing apparatus adapted particularly for washing glasses, bottles, and similar articles. It is an object of the 5 present invention to provide a washing apparatus whereby flowing water may be used to rotate the cleaning member and at the same time serve to rinse and clean the article being washed.

10 It is another object of the present invention to provide an apparatus of this class in which a portion of a stream of flowing water may be directed into the vessel being washed and a portion of the flowing water 15 used for rotating the cleaning mechanism.

Another object of the invention is the provision in a washing apparatus of this class of a turbine driven cleaning member which may also serve as a spray conductor.

20 Another object of the invention is the provision in a device of this class of a control device whereby the stream of water delivered to the vessel being washed may be controlled and the movement of the movable 25 cleaning member simultaneously regulated.

Another object of the invention is the provision of a device of this kind which will be simple in structure, economical of manufacture, and highly efficient in use.

30 Other objects will appear hereinafter.

The invention consists in the combination and arrangement of parts hereinafter described and claimed.

The invention will be best understood by a 35 reference to the accompanying drawings which form a part of this specification and in which,

Fig. 1 is a central vertical sectional view 40 of the invention showing parts in side elevation and parts broken away.

Fig. 2 is a sectional view taken on line 2-2 of Fig. 1.

Fig. 3 is a sectional view taken on line 3-3 of Fig. 1.

45 Fig. 4 is a sectional view taken on line 4-4 of Fig. 1.

The invention comprises a head 7 which is 50 preferably formed from metal. A central opening or passage 8 is formed in the head 7 and a bushing 9 is pressed into the passage

8 as a press fit. A chamber 10 is formed in the head 7. A tubular fitting 11 is threaded into the head and provided with the coupling 12 whereby attachment to a faucet may be made to supply water under pressure, the 55 device being adapted for coupling to the city pressure supply of water. Positioned in the bushing 9 and rotatable therein is an inner bushing 13. A supporting post 14 is rotatably mounted in the bushing 13. Fixedly 60 mounted on the end of the post 14 is a hub 15 radiating outwardly from which are the turbine blades 16. Passages 17 which are inclined to the horizontal serve to permit the passage of water from the chamber 10 against 65 the turbine blade 16. A cylindrical housing or shell 18 serves as a closure for the turbine blades and also as a support for the apparatus. The post 14 is formed tubular at its upper portion so as to communicate through 70 the passage 19 formed in the fitting 20 with the tubular arm 21 which extends upwardly therefrom and which is preferably tapered and provided with a spray nozzle 22 at its upper end to which are secured one end of 75 the chains 23. A circumferential recess 24 is formed on the inner surface of the bushing 13 which communicates with the radial openings 25 formed in this bushing. The fitting 11 is secured in the head 7 so as to discharge 80 water into the passage 26 from which it may pass through the openings 27 formed in the outer or stationary bushing 9. Through the openings 25 into the recess 24 from which it may pass through the opening 28 formed in 85 the bushing 9 into the chamber 10 a part of this water will also pass through the openings 29 into the tubular portion of the post 14 and thence upwardly through the tubular member 21. A rod 30 is secured to the head 31 of the bushing 13 so that the bushing 13 may 90 be rotated relatively to the bushing 9 so as to bring the openings 25 out of registration with the openings 27 and 28 which are formed in the bushing 9. In this way the bushing 13 serves as a valve to regulate the flow of water into the chamber 10 and into the member 21. A locking ring 32 is provided with a resilient 95 ring 33 for locking the post 14 against axial 100

movement while at the same time permitting its free rotation within the bushing 13.

After water is delivered through the fitting 11 and the bushing 13 turned to bring the opening 25 into registration with the opening 27 water will issue into the recess portion 24 from which it will pass into the member 21 and into the chamber 10. The water passing into the chamber 10 will pass out through the passages 17 so as to rotate the turbine head, thus effecting a rotation of the member 21. A glass bottle or other article pressed in inverted relation on the member 21 will be easily and quickly cleaned by being brought into contact with the cleaning chains 23 and also because of the spray of water which will issue from the member 21.

It has been found that with this device coupled to the ordinary city pressure water supply the arm 21 may be rotated at a high speed and sufficient water will be supplied to provide an ample spray for rinsing and cleansing purposes.

It is believed obvious that the device is of a compact nature and may be economically manufactured.

While I have illustrated and described the preferred form of my invention, I do not wish to limit myself to the precise details of structure shown but desire to avail myself of such variations and modifications as may come within the scope of the appended claims.

Having thus described my invention, what I claim as new and desire to secure by Letters Patent is:

1. A device of the class described, comprising: a head, a bushing mounted in said head; said head having a chamber formed therein; a second bushing rotatably mounted in said first mentioned bushing, said bushings having openings formed therein adapted for registering upon rotation of said second mentioned bushing to a pre-determined position; a conduit for delivering liquid into said head, said head having a passage leading from said conduit to said openings in said bushings; a supporting post rotatably mounted concentrically of said second bushing and having openings formed therein communicating with an internal recess formed in said second bushing in communication with the openings formed in said second bushing, said supporting post being tubular at and above said openings; a tubular arm mounted on the upper end of said post and projecting upwardly therefrom; a turbine wheel carried on the lower end of said post, said head having passages formed therein for directing water from said chamber against said turbine for rotating said post.

2. A device of the class described comprising: a head having a chamber formed therein; a bushing rotatably mounted in said head and having an internal groove com-

municating with a pair of spaced openings formed in said bushing, one of said openings communicating with said chamber and the other with an inlet passage formed in said head upon rotation of said bushing to a pre-determined position; an inlet conduit communicating with said passage in said head; a tubular member projected through said bushing and projecting beyond the ends thereof; a turbine wheel mounted on the lower end of said tubular member, said head having passages formed therein for directing water from said chamber against said wheel for rotating the same.

In testimony whereof I have signed the foregoing specification.

GEORGE GEDDES.
